TRAY TABLE

Walter E. Jogwick, Parkersburg, and
Eli H. McLaughlin, Vienna, W. Va.

Application February 15, 1946, Serial No. 647,841

3 Claims. (Cl. 311—85)

1

This invention relates to a tray-table, and more particularly to a novel structure adapted to be used either as a tray or table.

An important object of the invention is to provide a device of the character referred to having a body in the form of a tray or the like and having associated therewith a plurality of legs adapted to be readily released by the finger of the operator, while holding the tray, to move downwardly to a supporting position whereby the device is usable as a small table in the nature of a coffee table.

A further object is to provide a novel tray-table having legs normally folded out of the way against the bottom of the tray body, and to provide novel operating means adjacent the respective ends of the tray body for swinging the legs downwardly to operative positions and for swinging them upwardly into horizontal inoperative positions adjacent the bottom of the tray body.

A further object is to provide novel means for latching the legs in either operative or inoperative positions, the means for moving the legs between such positions being operative for initially releasing the latching means.

A further object is to provide a device of the character just referred to wherein lever devices are employed for moving the legs, and wherein such devices initially act as cams to release the latching means whereupon the lever means become operative for swinging the legs to the desired positions.

Other objects and advantages of the invention will become apparent during the course of the following description.

In the drawings we have shown one embodiment of the invention. In this showing:

Figure 1 is a perspective view of the device in position to be used as a table.

Figure 2 is a section taken substantially on line 2—2 of Figure 1.

Figure 3 is an enlarged fragmentary end view of a portion of the tray body showing the ends of the operating lever elements.

Figure 4 is a bottom plan view of the device showing the legs folded to inoperative positions.

Figure 5 is an enlarged longitudinal sectional view on line 5—5 of Figure 4, parts being broken away, and the operating parts being shown in the position they will occupy with the legs folded.

Figure 6 is a similar view on line 6—6 of Figure 4, parts being shown in elevation and parts being broken away, the legs and associated elements being shown in operative positions, and.

Figure 7 is a detail perspective view of a pair of the lever devices.

2

Referring to the drawings, the numeral 10 designates the tray or table body as a whole which is preferably, but not necessarily, formed of molded material, such as one of the plastics now commonly employed for making furniture and similar articles. The body 10 comprises a top 11 surrounded by an integral upwardly extending portion 12 serving as a retaining flange around the tray or table top. Outwardly of the portion 12, the material forming the tray or table top extends downwardly to form a flange 14 along opposite sides of the table while at the ends of the device similar flanges 15 are formed. The flanges 14 may extend inwardly and downwardly as at 16 (Figure 2).

The body 10 is preferably provided beneath the top 11 with an integral stiffening member 18 which, adjacent the ends of the top 10, divides as at 19 (Figures 2 and 4) to provide a space 20 adjacent opposite ends of the device in which certain operating parts to be referred to are arranged.

The pair of members 19 at each end of the table or tray are associated with elements to be described, and since the elements at each end of the device are identical, only one set need be described in detail. Each pair of members 19 act as bearings to support a shaft 22 extending transversely of the table, the ends of this shaft extending through openings 23 in the skirt 14 to act as bearings for the ends of the shaft. Adjacent each side of the body 10, each shaft 22 carries a pair of collars 24 having projections 25 extending into the adjacent ends of tubular legs 26. The collars 24 and legs 26 may be of any desired type, and the collars 24 definitely may be split down through the projections 25 and the split collars may be clamped to each shaft 22 as at 27.

Within each space 20 is arranged a collar 30 grooved as at 31 between annular flanges 32. The collar 30 may be fixed to its shaft 22 by a set screw 33 or any other suitable means.

The groove 31 of each collar 30 has arranged therein one end of a lever 36 provided with a finger piece or handle 37 projecting through a groove 38 formed in the material from which the body 10 is molded, the portion of the material in which the groove 38 is formed being extended outwardly to form a handle 39 at each end of the table. Such handle preferably has its top surface curved downwardly and outwardly as clearly shown in Figures 1, 5 and 6. Each lever 36 is pivoted to the associated collar 30 by a transverse pin 42 extending through the flanges 32. The

portion of the lever within the groove 31 curves around the portion of the collar forming the bottom of the recess 31 normally out of contact therewith to provide for limited turning movement of each lever 36 about the axis of its pin 42. Each lever 36 is grooved as at 44 to reduce the width of the portion of the lever within the groove 31 so that such portion of the lever is of a thickness not over one-half of the width of the groove 31.

A second lever element 46 is arranged in each groove 31 and has one of its ends mounted on a pin 47, similar to the pin 42, and extending through the associated flanges 32. At its opposite end, each lever 46 is provided with a finger piece 48, and intermediate its ends, each lever 46 is grooved as at 49 so that the portion of such lever is adapted to cross and clear its associated lever 36. Each lever 46 also operates around the bottom of its associated groove 31 in normal spaced relation thereto so as to provide for limited turning movement of the lever about its pin 47.

A spring latch device is operative in conjunction with both of the collars 30 to fix them in either of their two positions to be referred to. The latch device comprises an elongated leaf spring 50 secured intermediate the length of the body 10 to the reinforcing rib 18, as at 51, (Figures 5 and 6). From the securing members to its ends, the spring 50 is free and such ends exert an upward force. The spring ends are turned upwardly as at 52 to selectively enter notches 53 or 54 formed in the flanges 32 of the collars 30. Depending upon which notches are engaged by the spring ends 52, the legs 26 will be held either in the inoperative positions shown in Figure 4 or in the operative positions shown in Figures 1, 2 and 6. It will be noted that the legs 26 of one end of the device are spaced a slightly greater distance than those at the other end, thus permitting one set of legs to swing in between the other set when the legs are in their inoperative positions, as shown in Figure 4.

The operation of the device is as follows:

Used as a tray, the device is light and easily transported merely by grasping the handles 39. If it is desired to use the device as a table, the operator need merely depress the finger pieces 48. With the legs in folded or inoperative positions, the lever devices 36 and 46 will occupy the positions shown in Figure 5. In such positions of the parts, the spring ends 52 will engage the notches 53 and a portion of each lever device 46, at a point spaced from its pivot 47, will contact the adjacent spring end 52, such spring end bridging across each of the grooves 31 as shown in Figure 2. Accordingly, when the finger pieces 48 are depressed while supporting the body of the device above the floor, lever devices 46 will swing to depress the spring ends 52 and release them from the notches 53. The legs 26 will then swing downwardly by gravity through slightly more than a 90 degree turn to operative positions shown in Figures 1 and 6. When such positions of the legs are reached the notches 54 will move into registration with the spring ends 52, whereupon the latter snap into notches 54, thus limiting further turning movement of the legs. Such engagement of the spring ends 52 in the notches 54 fixes the legs against turning movement in either direction from operative position, thus rendering the device ready for use as a rigidly supported table.

When the legs swing to the operative positions

referred to, rotation of the collars 30 will move the lever elements to the positions shown in Figure 6. The lever elements rotate bodily with their associated collars 30 because of the limited turning movement of the levers relative to their pivot pins.

The operation of returning the legs to inoperative positions may be performed very easily while supporting the device by the handles 39. With the fingers of the two hands arranged beneath the handles 39, the operator may place his thumb over the lever ends 31 to turn the lever elements 36. This operation initially rocks the levers 36 on their pivots 42, turning movement of the levers 36 being permitted to a limited extent before the levers contact with the bottoms of the grooves 31. Such limited turning movement of the levers 36 causes the ends thereof to cam the spring ends 52 out of the notches 54. Such turning movement of the left hand lever 36 in Figure 6 takes place in a counter-clockwise direction while the other lever 36 turns in a clockwise direction.

After the spring ends 52 have been disengaged from the notches 54, points on the lever 36 a little above the pivot pins 42 will engage the bottoms of the grooves 31 to prevent further turning movement of the levers independently of the collars 30. Further forces transmitted to the handles 37 to tend to turn the levers 36 in the directions referred to will then transmit rocking movement to the collars 30 and the legs may be swung upwardly to their horizontal positions. When such positions are reached, the spring ends 52 will snap into the notches 53 to support the legs in inoperative positions. The device thereupon may be used or transported as a tray.

From the foregoing it will be apparent that the present device may be readily used either as a tray or table. Food stuffs may be placed on the tray 11 when the device is used as a tray, whereupon the device may be carried to any desired point and, while holding the body 10 in a horizontal portion above the floor, the operator may depress the finger pieces 48, to drop the legs to their operative positions. When the use of the device as a table has been finished, the operator may merely lift the device by the handles 39 to move the legs themselves vertically from the floor, whereupon the thumbs of the operator's hands may be readily employed for swinging the legs to inoperative positions. The device thereupon quickly becomes a tray which may be readily carried out of the room.

The device may be economically manufactured and in practice is of highly ornamental appearance. The entire body of the device may be readily made of molded plastic of any desired color.

We claim:

1. A tray-table comprising a normally horizontal body, parallel shafts arranged beneath said body each adjacent one end thereof, a pair of legs fixed to each shaft to swing therewith, said legs being movable between inoperative positions beneath and approximately parallel to said body and operative positions projecting downwardly from said body to support said body as a table, latch devices for holding said shafts against turning movement when said legs are in said inoperative positions, a lever device adjacent each end of said body engageable with the associated latch device whereby turning movement of said lever devices will release said latch devices where-
75 by said legs will swing downwardly by gravity to

said operative positions, said latch devices being operative when said legs are in said operative positions for preventing turning movement of said shafts, and an operating lever associated with each shaft and having a portion engageable with its latch device whereby initial turning movement of said operating levers in one direction will release said latch devices, said operating levers having mechanical connection with said shafts whereby turning movement of said operating levers in said direction, after said latch device has been released, will swing said legs to said inoperative positions.

2. A tray-table comprising a normally horizontal body, a rocking structure comprising a shaft beneath said body adjacent each end thereof, and a pair of legs fixed to each shaft, each shaft being rockable whereby its associated legs are adapted to swing between inoperative positions adjacent and parallel to said body and operative positions projecting downwardly from said body to support the latter as a table, each of said rockable structures having a pair of notches circumferentially spaced from each other, a spring finger engageable in one notch of each rockable structure when said legs are in said inoperative positions and engageable in the other notch of such rockable structure when said legs are in said operative positions, a lever device pivoted to each rockable structure and bodily movable therewith, each lever device being engageable with the adjacent spring finger to release it from the slot with which it is engaged when said legs are in said inoperative positions, and an operating lever pivotally connected to each rockable structure and bodily movable therewith and having limited turning movement relative thereto, each operating lever being engageable with the adjacent spring finger and operative during its said limited movement for releasing said finger from said rockable structure, each operating lever being thereafter operative for bodily turning its rockable structure to move said legs from said operative positions to said inoperative positions.

3. A tray-table comprising a normally horizontal body, a rockable structure including a shaft

beneath and adjacent each end of said body, said shafts being parallel to each other, a pair of legs carried by each shaft and movable therewith between inoperative positions adjacent and parallel to said body and operative positions projecting downwardly from said body to support it, a collar carried by each shaft, each collar having a pair of circumferentially-spaced notches, a spring finger selectively engageable in the notches of each collar when the associated legs are respectively in their inoperative and operative positions, a lever device pivoted to each collar and engageable with the associated spring finger to release it from the notch which it engages when said legs are in said inoperative positions whereby said legs swing downwardly by gravity to their operative positions, and an operating lever pivoted to each collar for bodily movement therewith and having limited turning movement relative thereto, each operating lever being engageable with the associated spring finger and operable during said limited movement for moving such spring finger from the notch with which it is engaged when said legs are in said operative positions, said operating levers being thereafter operative through said collars to turn said shafts and swing said legs from said operative to said inoperative positions.
